UNITED STATES PATENT OFFICE.

CHARLES R. SHORT, OF DETROIT, MICHIGAN, ASSIGNOR TO GENERAL MOTORS COMPANY, OF DETROIT, MICHIGAN, A CORPORATION OF NEW JERSEY.

VALVE-ACTUATING DEVICE FOR HYDROCARBON MOTORS.

Application filed April 21, 1917. Serial No. 163,754.

To all whom it may concern:

Be it known that I, CHARLES R. SHORT, a subject of the King of Great Britain, and resident of Detroit, Wayne County, State of Michigan, have invented certain new and useful Improvements in Valve-Actuating Devices for Hydrocarbon Motors, of which the following is a specification.

This invention relates to hydrocarbon motors, and more particularly to the valve mechanism thereof.

One of the objects of this invention is to provide a valve mechanism and its operating means with connections adapted to automatically compensate for and take up any variations in the length of its various parts.

Another object of this invention is to provide a motor, having a poppet valve mechanism with a device between the valve member and its operating means for preventing any improper clearances between these parts.

Another object of this invention is to provide a valve mechanism with a cushion device between the valve proper and its actuating means.

With the constructions of poppet valve mechanisms previously used in internal combustion engines, it has been found necessary to maintain certain clearances between the valve proper and its actuating means. With such constructions, an undesirable click or tap is produced, when this clearance is rapidly taken up. To overcome this and other difficulties, I have provided means for maintaining each of the connecting parts in contact with the others, and also for cushioning the impact blow between the actuating means and the valve mechanism.

These and various other objects will more clearly appear from the following description, taken in connection with the accompanying drawings, which form a part of this specification, and in which:

Figure 1 is an end elevation, with portions broken away, of an internal combustion engine, illustrating a preferred form of my invention; and

Figure 2 is an assembly view, with portions in vertical section, of the tappet and connection, illustrated in Figure 1.

Referring to the drawings, 10 represents the motor crank case in which is mounted a shaft 11, provided with cams 12. A cylin-

der block 13, having a spring closed poppet valve mechanism 14, may be mounted on the crank case. A rocker arm 15 is adapted to have its central portion 16 sleeved on a shaft 17 which is supported in an arm 18, this arm being detachably mounted on the cylinder head 19 as by bolts 20. One end of the rocker arm 15 is provided with a spherical face 21, which is adapted to abut against the upper end 22 of the poppet valve member 14. Slidably mounted in a guide sleeve 23, which is secured by bolts 24 to the crank case 10, is a tubular tappet member 25, which is provided at its lower end with a contact shoe 26, adapted to be actuated by the cam 12. A hollow plug 27 is adapted to be secured in any well known manner, such as by welding to the upper end of this member.

The plug is formed with a hollow cylindrical interior 28, having a tapered end 29 and a piston member 31 having a tapered end portion 32 is adapted to be slidably mounted in the plug with a spring 33 between the upper portion of the plug and the out-turned flange 34 on the piston member.

A valve rod 35 is adapted to have its upper end 36 preferably adjustably connected with a button 37, secured to the short end 38 of the rocker arm 15, and to have its lower end 39 resting in the interior of the piston member 31.

The lower end 32 of the piston member is provided with a port 41 connecting its interior and exterior portions adjacent its bottom. It is to be noted that the parts just described are so correlated as to function a dash pot and cushion connection between the upper end of the valve tappet and the valve proper.

With the parts in the position illustrated in the drawings, that is with the tappet resting on the inactive portion of the cam 12, the relatively light spring 33 will maintain the tappet 25, operating rod 35, rocker arm 15 and the rocker arm 22 of the poppet valve member 15 in contact with abutting parts, thus preventing any clearance between these various members.

There will be sufficient clearance provided between the interior of the piston member 31 and the exterior of the lower end 39 of the operating rod 35 to permit the lubricant

which flows from the rocker arm 15 and the upper end of the rod 35 to be carried to the bottom 40 of the member 31, where it will be drained through the port 41 between the lower end 32 of the piston member and the end 29 of the cylindrical member 27. It is to be noted that the upper end of the piston member 34 is counter-sunk at 42 for retaining a small pool of oil around the adjacent portion of the rod 35.

As the cam shaft 11 rotates, bringing the active portion of the cam 12 against the contact shoe of the tappet member 25 and begins to raise the same, the initial movement 15 will cause a compression of the relatively light spring 33 and the lower end of the piston member 31 on the oil therebeneath, will thus cushion the relative movement between the various connecting parts, and any noise 20 is thereby obviated. Of course, after the valve mechanism has been opened, and the receding portion of the cam 12 is brought against the tappet member 25, the spring and dash pot will function to release all 25 pressure of the piston member on the oil cushion therebelow and permit more oil to flow into the dash pot if necessary.

It must also be noted that the oil filling the spaces about the rod 35 and the piston member 31 will cushion all side faces with a film of oil and silence any side movement 30 on the part of the several elements in relation one to the other.

It will be thus seen from the foregoing description, that I have provided, in a very simple and effective manner, an efficient clearance compensator and yielding connections for a valve mechanism, particularly of the poppet valve type, though it will be understood that my invention will not be necessarily limited to such an application.

While I have described and will specifically claim what I deem to be a preferred embodiment of my invention, it will be obvious to those skilled in the art, that various modifications and changes may be made without departing from the spirit and scope hereof.

Having thus described my invention, what

I claim and desire to secure by Letters Patent is:

1. In an internal combustion engine, the combination with a valve mechanism, a tappet, a rod and connection therebetween comprising a cylinder, a hollow piston 55 therein having a port connecting its interior and exterior, and a rod having one end mounted in said piston.

2. In an internal combustion engine, the combination with a valve mechanism, a tappet having an inner bore, a piston fitting said bore and having a central orifice in communication with said bore, a rod stepped 60 in the central orifice of said piston, and means for yieldingly supporting said rod.

3. In an internal combustion engine, the combination with a valve mechanism, a tappet having an inner bore, a piston fitting said bore and having a central orifice in communication with said bore, a rod stepped 70 in the central orifice of said piston, and means for yieldingly supporting said piston.

4. In valve mechanism of the class described, a reciprocating tappet having a liquid receiving chamber at its upper end; a piston operating within said chamber and having a liquid receiving chamber of less area than the chamber in said tappet; a valve operating rod the lower end of which extends into the chamber in said piston; a spring intermediate said tappet and said piston; and a liquid passage extending between said two liquid receiving chambers.

5. In valve mechanism of the class described, a reciprocating tappet having a liquid receiving chamber at its upper end; a piston operating within said chamber and having a liquid receiving chamber of less area than the chamber in said tappet; a valve operating rod the lower end of which extends into the chamber in said piston; means for moving said piston out of the chamber in said tappet; and a liquid passage in said piston and through which said two liquid receiving chambers are placed in communication with one another.

In testimony whereof I affix my signature.

CHARLES R. SHORT.
